UNITED STATES PATENT OFFICE.

HOMOBONO GONZALEZ, OF PARANAQUE, PHILIPPINE ISLANDS.

PENCIL-TIP AND PENHOLDER.

1,383,298.

Specification of Letters Patent.

Patented July 5, 1921.

Application filed July 8, 1919. Serial No. 309,320.

To all whom it may concern:

Be it known that I, HOMOBONO GONZALEZ, a citizen of the United States, residing at Paranaque, in the Province of Rizal and 5 Philippine Islands, have invented certain new and useful Improvements in Pencil-Tips and Penholders, of which the following is a specification.

This invention relates to a penholder attachment for lead pencils, which includes a tip or protector for the point of the pencil, and an object of the invention is to provide an attachment for lead pencils, whereby they may be easily and quickly converted into a 15 penholder, when desired.

Another object of this invention is to provide a cylindrical pencil tip, having pen retaining means carried thereby for retaining an ordinary pen point and also to provide a 20 sleeve slidably carried by the cylindrical pencil tip and adapted to be projected to house or inclose the pen point, when the latter is not in use and to embody means, for retaining the said sleeve in adjusted position.

Other objects of the invention will appear in the following detailed description, taken in connection with the accompanying drawing, forming a part of this specification, and in which drawing:

Figure 1 is a side elevation of the improved pencil tip and penholder showing it in position for use as a penholder.

Fig. 2 is a top plan of the improved pencil tip and penholder showing it adjusted for use 35 as a pencil.

Fig. 3 is a fragmentary plan of the pencil tip.

Fig. 4 is a detail view of the pen retaining means which is associated with the cylindrical pencil tip.

Fig. 5 is a section on the line 5—5 of Fig. 3.

Fig. 6 is a plan of the sliding sleeve.

Fig. 7 is a plan of the penholder removed from connection with a pencil, and

Fig. 8 is a cross section on the line 8—8 of Fig. 7.

Referring more particularly to the drawing, A indicates an ordinary lead pencil, in connection with which the improved pencil 50 tip and penholder is used.

The pencil tip and penholder comprises a cylindrical body 1, having one end portion 2 thereof enlarged in diameter, and split longitudinally as shown at 3, to permit it to 55 spread slightly for mounting over the end of the lead pencil A. The major portion of the

cylindrical body 1, which is adapted to extend beyond or outwardly from either end of the pencil A, is reduced in diameter with respect to the portion 2, thereby forming a shoulder 4 which limits the mounting of the body upon the pencil. A pen retaining member 5 is mounted in the outer end of the reduced portion of the body 1 and this member is constructed of suitable spring or resilient material, being substantially cylindrical in shape and formed from a single piece of metal bent to provide a longitudinally extending slot or opening 6 in the pen retainer in which engages an instruck portion 7 formed near the outer end of the constricted portion of the body 1, for preventing rotary movement of the resilient pen retainer 5 within the body 1. This pen retainer 5 is adapted to expand, for engaging a pen point 70 as indicated at B and frictionally engages it and forces it against the inner surface of the cylindrical body 1 to retain the pen in place. The instruck portion 7 will also afford means for limiting the insertion of the pen point B 80 into the body 1.

A sleeve 8 is slidably mounted upon the reduced portion of the body 1, and it is adapted to be extended over the pen point B, to protect the latter when not in use, as clearly 85 shown in Fig. 2 of the drawing, while it is moved over the reduced portion of the body 1 to permit the pen point B to be exposed for use.

The sleeve 8 is provided with a longitudinally extending slot 9 therein, and with a pair of arcuate out-struck portions 10 and 11 at its inner and outer ends respectively. These out-struck portions communicate with the longitudinal slot 9, and are adapted to 95 receive therein a knob or out-struck portion 12 which is formed on the body 1, near the outer end thereof. When the outstruck portion 12 is moved into the recess formed by the arcuate outstruck portion 11, by rotating 100 the sleeve 8 upon the body 1, as shown in Fig. 8 of the drawing, longitudinal movement of the sleeve will be prevented, and the latter will be retained upon the reduced portion of the body 1 to permit the pen B to 105 be used, however when it is desired to utilize the pencil, the sleeve 8 is rotated to position the knob 12 in the slot 9, and the sleeve 8 is moved longitudinally over the reduced portion of the body 1 until the knob is in alignment with the end of the outstruck arcuate portion 10 which opens into the slot 9, after 110

which the sleeve 8 is rotated, to move the knob 12 into the recess formed by the outstruck portion 10, thus locking the sleeve over the pen B and forming a housing for the said pen to prevent it from being mutilated during use of the pencil or when being carried about in one's pocket. When the device is used as a pen, it may, of course, be inserted over either the pointed or blunt end 10 of the lead pencil A, and when it is desired to use the point of the lead pencil, the tip or body 1 should be mounted upon the blunt end of the lead pencil leaving the point thereof free and when carrying the pencil 15 about in one's pocket, the body 1 could be mounted over the point of the pencil and the sleeve 8 shifted outwardly to house the pen point B, thereby preventing either the breaking of the point of the pencil A or the mutilation of the pen point B while it is carried. 20

Changes in details may be made without departing from the spirit of this invention, but;

I claim:

25 1. In a pencil tip and pen holder, the combination of a tubular body having one end enlarged for mounting upon one end of a pencil, pen retaining means carried by said body, a sleeve slidably mounted upon said body and limited in its movement over the body by the enlarged portion of the body, said sleeve provided with a longitudinally extending slot and a pair of oppositely extending arcuate outstruck portions at the 30 ends of the slot, an outstruck portion formed upon said body near the end remote from the enlarged end adapted to ride in said longitudinal slot upon sliding movement of the sleeve over the body and adapted to be moved into the recess formed by the outstruck portions to retain the sleeve in adjusted position with respect to the body to cover or uncover the pen point. 35

40 2. In a pencil tip and penholder, the combination, of a tubular body adapted for

50 mounting upon one end of a pencil, pen retaining means carried by the body, means for preventing rotation of the pen retaining means with respect to the body and to limit the insertion of a pen into the body, a sleeve 55 slidably carried by the body and adapted to be shifted to house a pen engaged by said pen retaining means, and means for retaining said sleeve in adjusted positions.

3. In a pencil tip and penholder, the combination, of a tubular body adapted for mounting upon one end of a pencil, cylindrical pen retaining means adapted for insertion into one end of said body, an in- 60 struck portion formed upon said body and adapted to receive said pen retaining means to prevent rotation thereof with respect to the body and to limit the insertion of a pen into the body, and a sleeve slidably supported by the body and adapted to be shifted to 65 house the pen engaged by said pen retaining means.

4. In a pencil tip and pen holder, the combination of a tubular body having one end enlarged for mounting upon an end of a pencil, pen retaining means carried by said body, a sleeve slidably mounted upon said body and positioned upon the small portion of said body in such manner that the exterior of said slideable sleeve is lodged in substantially the same plane as the exterior of said enlarged portion of the body, said sleeve provided with a longitudinally extending slot and a pair of oppositely extending arcuate outstruck portions at spaced ends of the 70 slot, an outstruck knob formed upon said body near the end remote from the enlarged end and adapted to ride in said longitudinal slot upon sliding movement of the sleeve and to be moved into the recess formed by either 75 of the outstruck portions to retain the sleeve in adjusted position for housing or unhousing the pen point. 80

HOMOBONO GONZALEZ.
